(57) **CLAIM**

The ornamental design for a cover for recessed light fixture, as shown and described.

DESCRIPTION

FIG. 1 is a side view of a cover for recessed light fixture, showing the new design.

FIG. 2 is a front view thereof;

FIG. 3 is another side view thereof;

FIG. 4 is a rear view thereof;

FIG. 5 is a top view thereof;

FIG. 6 is a bottom view thereof;

FIG. 7 is a perspective view thereof; and,

FIG. 8 is another perspective view thereof, wherein the cover is positioned below an example embodiment of a recessed light fixture for illustrative purposes.

The short broken lines in the drawings illustrate portions of the cover for recessed light fixture, which form no part of the claimed design.
